UNITED STATES PATENT OFFICE.

CHARLES HELD, OF MALDEN, MISSOURI.

IRONING-BOARD.

No. 916,554.

Specification of Letters Patent.

Patented March 30, 1909.

Application filed May 26, 1908. Serial No. 435,012.

To all whom it may concern:

Be it known that I, CHARLES HELD, a citizen of the United States, residing at Malden, in the county of Dunklin and State of Missouri, have invented certain new and useful Improvements in Ironing-Boards, of which the following is a specification, reference being had therein to the accompanying drawing.

10 This invention relates to improvements in ironing-boards, and has for its object the peculiar construction of a board of this class involving not only the structure of the board *per se*, but also of its support, which support 15 is an essential part of the complete or operative device.

Another object of the invention is the construction of an ironing-board, which comprises a minimum number of parts, is comparatively inexpensive to construct, and 20 simple and efficient in operation.

With these and other objects in view, the invention consists of certain novel constructions, combinations, and arrangements of 25 parts, as will be hereinafter fully described and claimed.

In the drawings: Figure 1 is a view, in side elevation, of my ironing-board. Fig. 2 is an inverted plan view of the body of my 30 device. Fig. 3 is a view, in side elevation of the body of the device, as it appears when placing the clamping-band thereon. Fig. 4 is a plan view of the clamping-band. Fig. 5 is a front view of the vertical clamp. Fig. 6 is 35 a fragmentary view of the body of the device, and showing particularly the groove formed therein.

Referring to the drawings by characters, 1 designates the primary and 2 the auxiliary 40 section of the body of the ironing-board. The primary section 1 is provided at one end with an inwardly-extending slot or cut-out portion 3, which cut-out portion 3 is provided at its inner end with an inclined, beveled wall 4 as shown by dotted line 4 in Fig. 3. The inner end of the primary portion 1 is also beveled, at 5, Fig. 3, in an opposite direction to the beveled inner end 4 of the slot or cut-out portion 3. The auxiliary section 2 is provided with a tongue or central extension 6, 45 which has, at its outer end, an inclined bevelled wall 7, conforming to the shape of the inclined wall or end 4; upon opposite sides of the tongue 6, and at the inner end of the section 2, there are formed inclined walls 5^a, 55 which also register with the inclined walls 5 at the inner end of the primary section 1.

Any suitable fastening means, as for instance, a pin 8, extends through the inner or beveled end of the primary section 1, and also through the tongue for pivotally securing the sections together. It is to be noted that the registering ends 5 and 5^a of the sections are inclined outwardly or in an opposite direction from the registering ends 4 and 7, and thereby constitute interlocking portions of the sections for producing a very efficient and strong connection for holding the sections in a horizontal position when the body or board is in use, but to further insure 60 of the fastening of the sections in their normal horizontal position, I provide movable locking means upon the bottom of section 1, which is permitted to overlap the lower portion of the tongue 7, and said locking means, preferably, 65 comprises a single bolt or threaded-member 9, having thereon a thumb-nut 10, which nut can be turned to overlap the tongue 6, as shown in Fig. 2, when it is desired to secure the sections 1 and 2 against pivotal movement. Therefore, by reason of the beveled 70 ends 4 and 7, and the locking device, I have produced a socket-like structure in which the tongue 6 extends when the auxiliary section 75 is in its normal closed, horizontal position. 80

Around the entire body of the board constituted by the sections 1 and 2, there is formed in the edge a groove 11, within which may be sprung the clamping band or loop 12. The band or loop 12 is, preferably, formed 90 from a single piece of material and may be constructed of any resilient material, for securely holding a cloth or covering 13 upon the body of the board. In position in the groove 11, a piece of fabric or felt 14, Fig. 6, 95 which acts as a filling means that is yieldable for permitting cloths or coverings 13 of different thicknesses to be used, if desired, and still tightly secure the coverings upon the board, as the felt or filling means 14 will give 100 in the groove sufficiently for obtaining this result.

When it is desired to place a cloth upon the board, all that is necessary is to swing the auxiliary section 2 upon its pivot constituted by the pin 8, as shown in Fig. 3, and place 5 the cloth over the board, and then place the ends of the clamping-band or loop 12 in the groove at the ends of the sections (as shown) and then press down on the outer end of the section 2, which will cause the band or loop 10 to spring into the groove and securely clamp the cloth in position, as shown in Fig. 1; furthermore, the clamping-band 12 also constitutes fastening means, whereby when the sections are in their closed position, Figs. 1 15 and 2, the band will act as a fastening means, besides the thumb-nut 9, for the single-piece band extends across the abutting inclined edges 5 and 5^a of the sections, when positioned as shown in Fig. 1, and, therefore, the 20 band is of importance in my sectional body structure, and is decidedly different from merely a groove in a body and with a band extending therein, for the reason and function just stated.

25 Engaging the body of section 1, and positioned contiguous to its outer end, is a plate 15, having screws 16, Fig. 2, extending therethrough for fastening said plate to the bottom of the section. The plate is provided 30 with a hollow body 17, in which hollow body projects the stem 18 of the clamp 19. A set-screw 20 is threaded into the hollow body 17 for engaging the stem 18, when it is desired to fasten the body of my ironing-board 35 device in an adjusted position or against pivotal movement upon the stem 18, for it will be obvious that if the set-screw 20 is not clamped tightly, at its inner end, against the stem 18, the board *per se*, will have a free or 40 pivotal movement upon the same, whereby the operator can adjust the same to any desired position, irrespective of the kind of support upon which the clamp 19 is mounted, for the clamp 19 may be secured to a 45 window-frame, a table, a shelf, and still the board, *per se*, can be quickly adjusted to a convenient position for permitting the operator to easily use my device. The stem 18 of the clamp 19 terminates at its base in a 50 flat extension 21, which extension 21 is at the upper end of the angle body 22; the body 22 comprising a series of right-angularly disposed portions, which produces a very strong and efficient structure that terminates at its 55 lower end in a U-shaped body 23, which body is provided, preferably, on its lower portion with a rotatably-mounted clamping-member 24. The substantially U-shaped body is provided on its upper end with a laterally-ex- 60 tending flat flange 25 that projects beyond opposite sides of the vertical portion 22, and prevents the clamp from marring or injuring

the support to which it is attached, when the device is in use, owing to the strain or pressure placed thereon by pressing or ironing an 65 article or garment.

From the foregoing description, it is to be noted that I have provided a simple device, which can be easily transported, for the board or body, *per se*, can be quickly detached from a support and stored in a small amount of space, as well as the supporting clamp of the device, and owing to the adaptability of the ironing-device to any kind of a support, and the adjustable feature 75 of the body upon the stem 16, the device could be used in different positions, as for instance, in case a room is not provided with a table, for if there is sufficient room on the window to clamp the device thereto, this 80 is all that is necessary.

What I claim is:

1. An ironing board comprising two sections, one of which is cut-away at its central portion to provide a longitudinal 85 slot having its inner edge beveled, the outer end of the board on the opposite sides of the slot being also beveled, the other section having a tongue extending centrally therefrom and inserted into the slot and pivotally 90 secured thereto, said tongue having a beveled inner end reversely arranged from that at the inner end of the slot and adapted to contact therewith and said other section having beveled portions at its intersection with said tongue which are reversely arranged from those on the outer end of the board and adapted to contact therewith, and said first-mentioned section having means thereon which engages said tongue 95 to hold the two sections immovably together, substantially as specified.

2. In an ironing-board, the combination with a support, of a body pivotally mounted upon said support, said body comprising a 105 primary and an auxiliary section, said primary section provided in its inner end with a longitudinally-extending slot, producing a bifurcated end upon said section, said slot terminating at its inner end in an 110 inwardly-extending, inclined wall, and said section provided at its inner end with a pair of outwardly-extending, inclined, transverse edges, said auxiliary section provided with a central, longitudinally-extending 115 tongue positioned in the slot of the primary section, a pin extending through the tongue and through the bifurcated portion of the primary section for pivotally securing the tongue in said slot, said tongue provided 120 with an outwardly-extending, inclined wall at its inner end and adapted to engage the similarly-constructed wall of the slot, said auxiliary section provided at its inner end

with outwardly-extending, inclined walls adapted to engage the similarly-constructed walls at the inner end of the primary section, when said auxiliary section is in its normal 5 horizontal position, and locking means movably mounted upon the under face of the primary section and adapted to overlap the tongue near its inner end for securing

the same against pivotal movement upon the primary section.

In testimony whereof I hereunto affix my signature in presence of two witnesses.

CHARLES HELD.
